RALPH C. EMERY, OF NEWTON, MASSACHUSETTS.

INDICATOR OR TIMER.

1,131,498.

Specification of Letters Patent.

Patented Mar. 9, 1915.

Application filed October 18, 1912. Serial No. 726,407.

To all whom it may concern:

Be it known that I, RALPH C. EMERY, a citizen of the United States, residing at Newton, in the county of Middlesex and State of Massachusetts, have invented new and useful Improvements in Indicators or Timers, of which the following is a specification.

This invention relates to an improved indicator or timer for use in radio-telegraphy and in other connections to which it is suited.

As applied to radio-telegraphy the purpose of the invention is to provide means to increase the effective speed of sending in cases where the receiving operator is subjected to recurring disturbances, such as the blowing of a whistle in a fog.

It is also a purpose of the invention to provide means to communicate to the bridge of a vessel, directly or by relay, the time when a distant vessel is blowing its whistle, thus enabling the pilot to estimate the distance of that vessel, or to change the time of his own whistle so that he can hear the other.

The operator's room on a ship not infrequently is arranged on the boat deck or otherwise so close to the steamer's whistle that the operator cannot hear an incoming message with certainty while the whistle is blowing. The request to the sender to repeat, and the ensuing repetition, which also may be interrupted, cause serious delay, particularly if the steamer be blowing twice or three times each minute as some fast steamers do. The purpose of the present invention, when applied to that situation, is to provide an indicator in the distant ship that will enable its operator to send only at times when the whistle on the receiving ship is not blowing.

One form of apparatus by which the objects of the invention are accomplished is shown in the accompanying drawings, in which—

Figure 1 is a front elevation; Fig. 2 is a side elevation of the same, partially in vertical medial section; and Fig. 3 is a front elevation of another embodiment of the invention with a diagrammatic indication of other apparatus and connections.

In the drawings 10 represents a case containing ordinary clock work adapted to drive a hand 11 which makes one complete circuit of the dial 12 in each minute, the

dial being divided into seconds. In connection with this dial is a movable screen 13 formed in two opposite lobes and adapted to cover or delimit portions of the dial. One or more auxiliary screens 14 are rotatable on the same axis, and can be set to augment the area covered by the screens 13. In the construction illustrated the screens 13 are supported on an annular casing 13' which is rotatable around the casing of the dial, so that the screens can be moved to any desired angular position on the dial. They are cut in the form of sectors; and the auxiliary screen portions 14 are cut likewise in the form of sectors, and are supported from a hollow pivot 15 at the center of the portion 13. A handle 16 is provided for conveniently setting the position of the screen 14 with respect to its supporting part 13; and the latter is conveniently rotatable on its annular bearing 13' around the clock casing. Being approximately balanced, each part retains any position in which it is placed, with the aid of such little friction as naturally occurs. When it is to be used in connection with a steamer's whistle, the sector of the screen 13 is preferably made the equivalent of four seconds of time, four seconds being the minimum allowed by law for a blast of whistle in a fog, although six or eight seconds is not unusual practice; and the auxiliary screen 14 is of similar size so that it can be slipped over the screen 13, to register with it precisely so that the two together cover only four seconds, this being the position when the stop 14' has engaged the adjacent edge of screen 13.

The use of the apparatus in connection with radio-telegraphy is as follows, it being assumed that both operators are equipped with an indicator of the sort described: The receiving operator acquaints the sending operator with the precise time when his whistle begins and ceases its blast, as for example, by beginning and ending a dash of radio-telegraphy simultaneously with the beginning and ending of his whistle blast. The operator on the sending ship, receiving this dash, sets his indicator so that the screen 13, or the combination of his screen 13 and 14, marks the beginning and ending of the blast on the ship to which he is sending. The receiving operator also informs him whether the blasts are one, two, or three per minute. The sending operator then resumes the sending of his message, but interrupts it each

time the hand on his indicator is about to enter the area delimited by screens 13 and 14, and continues it again as soon as the hand emerges therefrom. He thus eliminates the 5 receiving operator's requests for repetition, and saves time which, as telegraphy is now practised, is wasted in the request and the repetition. This time may be quite considerable, inasmuch as the whistle of a steamer 10 traveling at high speed and blowing two or three times per minute occupies a considerable portion of the total time in a minute.

If the period be one per minute, the operator will set one of the lobes of the screen, 15 13, 14, to correspond with that and will ignore the other lobe. If the period be three per minute another apparatus may be used having three lobes; or it is feasible as illustrated in Fig. 3 to have three separate lobes 20 13" mounted on the same central pivot, one, two or three of which may be used at will, all being movable so that they can be condensed into one or can be extended into more than one. The operator on the receiving 25 ship, having set his own indicator to correspond with his own whistle and with the indicator which he has caused to be set on the ship with which he is working, can observe whether his whistle subsequently varies from 30 the time he has transmitted to the sending ship and thus can cause the indicator on that ship to be corrected if necessary. By observing when the hand is about to pass behind the screen, the receiving operator can 35 utilize the interval during which the sending ship will be silent in order to send a message himself. This enables the transmission of messages to go on in opposite directions, the operator on the ship with the whistle 40 sending while his own whistle is sounding, the operator on the original sending ship co-operating by stopping his sending, either abruptly or with the last complete word that can be finished before his indicator hand goes 45 under the screen, and being ready to receive during the ensuing interval.

It sometimes happens that two ships approaching each other in a fog are blowing their whistles at the same rate and at such 50 times that the sound of one reaches the other at such time as to be inaudible owing to its own whistle, or the echo of its own whistle. By means of the indicator above described, 55 the telegraph operator on that ship might nevertheless observe that the time given him for the whistle on the distant ship was coinciding with his own whistle, or nearly so, and could warn those on the bridge of that 60 fact, enabling them to change their own time of blowing, and so hear the approaching ship. Moreover the indicator may be extended by a relay device so that the indication as to the time when the whistle is actually blowing on the distant ship may be 65 signified audibly or visibly at the bridge of

the other ship; or mechanically at the operator's instrument or elsewhere. Apparatus for doing this is illustrated as consisting of a prolongation of the spindle 17, on which the hand 11 is mounted, through the glass and 70 hollow central pivot of the screen to the outside, where an arm 18 carrying a brush 19 may slip around synchronously with the hand 11. In this form one terminal, for example, the screen is connected to a battery 75 20, the other terminal being connected through an incandescent lamp 21, or a buzzer or other signal on the bridge of the ship, to the battery 13 and 14. These screens being 80 made of copper or carrying a copper contact piece, a circuit will be established, and the light or other signal operated on the bridge, simultaneously with the blowing of the whistle on the distant ship. This permits those on the bridge to know with precision 85 the time of blowing on that ship, particularly if the blowing be controlled automatically, and therefore precise in its intervals, a fact of which they may take advantage in several ways. One is that above described 90 when a whistle blown within hearing distance is nevertheless not audible to them because of its coinciding with their own whistle blast or its echo. This relay arrangement is indeed a more practical arrangement than a reliance upon the telegraph operator to discover such a coincidence. Another advantage gained is that when the 95 whistle of the distant steamer is audible through the fog, but is of unknown distance, 100 and the officer on the bridge learns by the indicator the time when said whistle is actually blown, he can compute the distance of the other ship from him in the fog by observing the interval between that time and the 105 time of his actual hearing of the whistle, and by making due allowance for wind, etc. A further variation which may be beneficial in some circumstances is to make the screens translucent instead of opaque, so that the 110 progress of the hand can be watched even while behind the screen. This is especially useful where the screened period is used for sending in the other direction, as it enables the sender to see when his time is about to 115 elapse, so not to start a word that will not be finished within it.

In the modification illustrated in Fig. 3 the lobes are all supported from the central pivot and no annular casing is required, being held by friction in whatever position they are placed. This also illustrates diagrammatically the connections last described and shows also how the same device may automatically lock the operator's key 22 so 120 that he cannot send, while the distant receiving operator is unable to hear, if the sending operator happens to neglect the visual indication of the screen. This is accomplished by providing a solenoid 23 in the 125 130

circuit, having a fiber plunger 24 which projects under the key 22. When a current flows the magnetic portion 25 of the plunger is attracted into the coil, causing the 5 non-magnetic portion to project farther and in so doing to pass under the key 22, thus locking it. When not thus locked, the sending operator's depression of the key 22 causes a signal to pass from the antennæ 26 10 which, striking the antennæ 27, may be heard by the receiving operator in the telephones 28, as indicated in diagram in Fig. 3.

By means of a simple spring catch 26 all three lobes in Fig. 3 may be locked together 15 in positions 120° apart; or one 180° apart from the other two; or all together; there being a pin on the spring 26 and holes in the disks underneath at proper places.

It is the object of the appended claims to 20 cover such features of novelty as exist in the invention disclosed herein; and it is to be understood that many variations may be made from the specific structure illustrated without departing from the scope of the invention as covered by the claims.

It is also particularly pointed out that the terms "second hand" and "dial" used in the claims are used in a broad sense. The hand may in fact advance by stages of any 30 length, as, for example, by half seconds or quarter seconds, or its progress may be continuous instead of intermittent. So also the dial referred to need not be marked as illustrated, although divisions of some sort 35 thereon will be found convenient.

I claim:

1. Apparatus adapted for use with a system of radio-telegraphy, comprising mechanism and an element driven thereby at a 40 regular rate through a circuit repeatedly; a screen extending over a definite part of the circuit; and means whereby the screen is rapidly adjustable to any position around the circuit, thereby indicating the time of 45 recurrent disturbances.

2. Apparatus adapted for use with a system of radio-telegraphy, comprising mechanism and an element driven thereby at a

regular rate through a circuit repeatedly; a screen, extending over a definite part of the 50 circuit, rapidly adjustable and extensible around the circuit, thereby indicating the time of recurrent disturbances.

3. In a system of radio-telegraphy, means to avoid recurrent disturbances of operation comprising the combination, at a sending station, of mechanism and an element driven thereby at a regular rate through a circuit repeatedly; means adapted to represent a period of disturbance, extending 60 over a definite part of the circuit, and means for rapid adjustment of the position thereof along said circuit, whereby a period of disturbance at the receiving station may be indicated recurrently at the sending station. 65

4. In a system of radio-telegraphy, means to avoid recurrent disturbances of operation, comprising the combination with sending means of a mechanism and an element driven thereby at a regular rate through a 70 circuit repeatedly; a device rapidly adjustable in position, arranged along said circuit and adapted to represent a period of disturbance at the receiving station; and a lock for the sending means actuated by conjunction of said driven element with said 75 device.

5. In a system of radio-telegraphy, means to avoid recurrent disturbances of operation, comprising the combination, at a 80 station having sending means, of a mechanism and an element driven thereby at a regular rate through a circuit repeatedly; a device rapidly adjustable in position, arranged along said circuit and adapted to represent 85 a period of disturbance at the receiving station; an electric circuit, and a signal operated thereby, upon conjunction of said device and said driven element.

Signed by me at Boston, Mass., this ninth 90 day of September, 1912.
